ROBERT WILLIARD PAIN, OF NEW YORK, N. Y., ASSIGNOR TO THE AEOLIAN CO., OF NEW YORK, N. Y., A CORPORATION OF CONNECTICUT.

MEANS FOR MODIFYING THE ACTION OF STRIKERS IN MECHANISM FOR PLAYING KEYBOARD INSTRUMENTS.

SPECIFICATION forming part of Letters Patent No. 730,958, dated June 16, 1903.

Application filed December 24, 1901. Serial No. 87,061. (No model.)

To all whom it may concern:

Be it known that I, ROBERT WILLIARD PAIN, of the borough of Manhattan, city, county, and State of New York, have invented a new and useful Improvement in Means for Modifying the Action of Strikers in Mechanisms for Playing Keyboard Instruments, of which the following is a specification.

This improvement relates to mechanisms for playing keyboard instruments, more particularly pianos.

The object of the improvement is to provide for variations of expression.

My invention consists in means for carrying out the above object, having the general construction substantially as hereinafter fully described, and shown in the accompanying specification and drawings.

In the accompanying drawings, Figure 1 is a top view of certain parts of a mechanism embodying my improvement and intended for playing a keyboard musical instrument. Fig. 2 is a vertical transverse sectional elevation of the parts necessary to illustrate my improvement.

Similar letters of reference designate corresponding parts in both figures.

A designates a number of strikers which are supported in a case at such height that they may extend over the keys of a keyboard instrument. It will be seen in Fig. 1 that some are longer than others. This is necessary so that they may act upon the black as well as upon the white keys. In the present instance these strikers are made in the form of bell-crank levers fulcrumed upon a pin or pins to a fixed part of the case. The upper arms extend horizontally over the keys of the instrument to be played, while the lower extend vertically downward to be operated by motors B. These motors B are of bellows-like construction and communicate internally with means whereby different pneumatic pressures may be established within them. These means may consist simply of suitable ducts connected with suction-bellows and appurtenant chambers. The movable board of each of these motors B is connected to the vertical arm of one of the striker-le-

vers. This connection may be advantageously made by means of a rod screw-threaded near the ends to receive nuts.

Adjacent to the strikers are retarders C. Each is to operate on one striker only. These retarders are shown as pneumatic and of bellows-like construction. Their immovable boards are fastened to the under side of a rail D, extending across the strikers at some distance therefrom. Two openings c' c² are afforded for communication between the interior of each retarder and the atmosphere. One of these openings c' is provided with a valve c³, operating automatically and consisting of a piece of sheepskin or similar material fastened at its two ends, so that it will cross the openings c', but will be free to rise away from the same. The movable board of each retarder is fastened in any suitable manner to an adjacent striker. The means shown for making the connection consists of a screw c⁴, passing through an extension of the movable board of the retarder and engaging with the striker. The other opening c² of the retarder is preferably larger and is controlled by a slide-valve c⁵, consisting of a plate having a hole which may be brought into line with the said opening or shifted out of line therewith.

A single plate may constitute valves c⁵ for a number of retarders, and this has been illustrated. Such a plate is connected by a pin c⁶ with a lever c⁷, fulcrumed between its ends to a pin c⁸ and connected at the other end to a rod c⁹, which is shown as extending to a position where it may be conveniently manipulated.

When the valve c⁵ of any retarder is open, that retarder will have no effect upon the striker with which it is combined; but when such valve c⁵ is closed the striker with which the retarder is combined will have to pull the movable board of the retarder away from the fixed board against pneumatic suction or the resistance offered to the inflow of air into that retarder through the opening c' under control of the automatic valve c³. Thus the action which the corresponding motor B would impart to such striker is modified by

devices controlled independently of the motors B, and variations of expression may thus be produced in playing.

The devices for retarding motion of strikers in the direction to operate the keys of a musical instrument might be described as devices adapted to produce legato effects. Instead of using such devices as retarders they might be used to increase and so accentuate the force of the strikers in acting upon the keys. Where pneumatic devices are thus employed in direct combination with the strikers, but for the purpose of increasing the force of the strikers, the valves ^c would of course have to be modified, so as to alternately establish communication between the pneumatics and the atmosphere, on the one hand, and a source of different pneumatic pressure which could advantageously be established either by suction or force bellows.

By the term "modifying devices" I mean to include retarding devices which are modifying devices opposing the action of the ordinary pneumatics, and I also mean to include other modifying devices which will add to or supplement the force of the ordinary pneumatics, because with either of these

kinds of devices the action of the strikers will be modified.

What I claim as new, and desire to secure 30 by Letters Patent, is—

1. The combination with strikers for operating the keys of a musical instrument, of pneumatic retarders each provided with two valves, one operating automatically and the other being manually controlled.

2. The combination with strikers and means for actuating them, of retarders acting directly upon said strikers, and both automatic valves and manual means for controlling the operation of the retarders.

3. The combination with strikers and means for actuating the same, of pneumatics for modifying the action of the strikers, each of said pneumatics being provided with both 45 automatic and manually-controlled valves.

In testimony whereof I have signed my name to this specification in the presence of two subscribing witnesses.

ROBERT WILLIARD PAIN.
